UNITED STATES PATENT OFFICE

WALTER P. SAUER, OF FOREST HILLS, NEW YORK, ASSIGNOR TO THEODOR SAUER COMPANY, OF NEW YORK, N. Y., A CORPORATION OF NEW YORK

EXTENSION TABLE

Application filed March 23, 1928. Serial No. 264,036.

This invention relates to improvements in extensible tables and has for one of its objects the provision of such a table provided with leaves hidden underneath a table top. The said table top being adapted when the leaves are extended to a predetermined position, to drop by gravity into a plane even with the plane of the leaves and form a continuous surface with the said leaves.

Another object of the invention is to provide means whereby the table top will automatically rise above the top surface of the leaves when the table is operated for extension or retraction.

A further object of the invention is to provide means whereby the table top will gradually assume a position even with the leaves at a predetermined point.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawings, where in similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purposes of illustration, is shown in the accompanying drawings, in which:

Figure 1 is a top plan view of one end of my improved table with some of the parts omitted therefrom.

Fig. 2 is a top plan view partly in section

of the table slides and table top raising means.

Fig. 3 is a sectional view taken on line 3—3 Fig. 1 showing the table in normal retractive position.

Fig. 4 is a similar view to Fig. 3 with some of the parts omitted therefrom, showing the leaves fully extended and spaced from the side edges from the table top.

Fig. 5 is a fragmental sectional view showing the table top in its lowered position and the leaves abutting the sides of table top.

Fig. 6 is a fragmental view showing the position of the table top raising means when the leaves are being retracted.

Fig. 7 is a sectional view taken on line 7—7 Fig. 3.

Fig. 8 is a front view of the rear or trip latch carrying plate.

Fig. 9 is a top plan view thereof.

Referring now to the drawings in detail 10 indicates a table supporting frame, and having secured thereto a stationary slide member 11 in operative relation with movable slides 12 and 13. At the bottom of the stationary slide 11 there is provided a gear 14 rotatively mounted on a bracket 15 secured to the said slide 11, the said gear 14 is in mesh with toothed racks 16 and 17 secured to the movable slides 12 and 13 respectively. Upon the movable slide 12 there is secured a leaf 18 and upon the movable slide 13 there is similarly secured a leaf 19 and overlying the said leaves there is a table top 20 normally resting upon the said leaves when the table is fully retracted.

Upon exerting an outward pull upon one of the leaves the table top 20 which is provided with depending arms 21 having rollers 22 mounted thereon and the said rollers normally resting in a cutout 25 in plates 24 secured to the movable slides 12 and 13, the said rollers will ride out of the notches or cutouts 25 on to a surface 26, thus raising the table top above the leaves 18 and 19. As the slides continue to be drawn outwardly the rollers 22 will be supported upon the top surface 26 of the plates 24 and upon the top of plates 27 and 28 and thus maintain the table top above the surface of the leaves to prevent the marring or scratching of said leaves. The plate 100

27 is provided with a cutout 29 and the plate 28 is provided with a similar cutout 30, which when the table is in contracted position will assume a position as shown in Fig. 3. During the outward movement of the slides 12 and 13 to extend the table, a pin 31 in the slide 12 will contact with a shoulder 32 on the plate 27 which is slidably mounted upon screws or studs 33 entering into the slide 11 and will bring the cutout 29 in the said plate 5 in alinement with the opening 30 in the rear plate 28 as shown in Fig. 4, the roller 22 meanwhile being prevented from dropping into the said opening by the extreme end of the 10 plate 24. Likewise a pin 35 in the slide 13 will have actuated similar plates 27^a and 28^a similarly mounted but on the opposite side of the inner stationary slide 11. Upon exerting an inward pressure upon the frame 10 the movable slides 12 and 13 will move inwardly carrying the plate 24 with them and the rollers 22 will ride down upon inclines 36 on the said plates and into the cutouts 36 of the plates 27 and 28 and the table top will 20 be gradually lowered to assume the position 25 shown in Fig. 5.

Up to the present time in tables of this nature, that is in tables where the table top will drop by gravity into alinement with leaves 30 when extended, no provision was made for a gradual dropping or lowering of the said table top, this caused considerable noise each time the table top was so lowered but with my improved raising and lowering means, 35 this noise is entirely eliminated.

Each of the rollers 22 when being lowered will come in contact with one end of latches 37 pivotally mounted on a stud 38 in the rear plates 28 and 28^a respectively and said latches will be tripped so that the ends 39 of 40 of the said latches will rest upon pins 40. The said latches are moved into contact with the said pins 40 by means of tension springs 41 coiled around studs 42 slidably supported in studs or posts 43 secured in the rear plates 45 28 and 28^a respectively, and operating in grooves or cutouts 44 in the stationary slide member 11, sufficient clearance being provided between the rollers 22 and the cutouts 29 50 and 30 to permit for this movement of the latches 37.

To retract the table the frame is again drawn outwardly with the leaves in the Fig. 4 position. During this movement the rollers 55 22 will have been lifted to the position shown in Fig. 6 by the inclined surface 36 on the plates 24 and the tension springs 41 will have moved the rear plates 28 and 28^a into position shown in Fig. 6, thus providing means 60 for maintaining the table top above the leaves 18 and 19 until said leaves are fully retracted, that is when they again assume the Fig. 3 position. Slots 46 and 47 in the plates 27 and 27^a and slots 48 and 49 in the plates 65 28 and 28^a will limit the movement of the

said plates when the table is being extended or retracted. The plates 27 and 27^a, as well as the plates 28 and 28^a, are returned to their normal position by means of pins 50 and 51 in the slides 12 and 13 respectively. 70

The plates 27 and 27^a are each provided with a pin 52 extending into a slot 53 in the rear plates 28 and 28^a. It will be seen that these plates 27 and 27^a may be moved outwardly by the pins 31 and 35 independently 75 of the plates 28 and 28^a as they are slidably mounted on the screws 23 but they will be returned simultaneously by the pins 50 and 51 against the tension of the springs 41.

It will also be seen that due to the gear and rack arrangement the slides 12 and 13 will move in opposite directions and carry their respective leaves outwardly of the table top when extended and inwardly when retracted. 80

It is to be understood that a second set of 85 slides and table top raising and lowering mechanism, as above described, is provided at the opposite end of the table.

From the above it will be seen that I have provided an extensible table having means 90 for maintaining a table top above the leaves thereof when said leaves are being extended or retracted and for gradually lowering the said table top gradually and silently lowering the said table top when the said leaves are 95 being extended.

Having described my invention, what I claim as new and desire to secure by Letters Patent is:

1. In an extensible table, a stationary slide 100 a movable slide in operative engagement therewith, a leaf secured to the said movable slide, a table top normally overlying the leaf when in retracted position, a depending projection on the table top, a member on the movable slide with which the said projection intermittently contacts to maintain the table top at a predetermined height when the leaf is being extended or retracted, plates superposed upon each other, provided with cutouts 105 normally out of alinement and slidably mounted on the fixed slide to maintain the table top in raised position at a predetermined point in the travel of the movable slide, means on the movable slide for alining the cutouts in the plates when the movable slide is nearing its outward limit of travel, and a cam on the member fixed to the movable slide to permit the depending projection on the table top to enter the cutouts so that the 110 said table top may gradually be lowered to a plane even with the leaf when the said leaf is partially retracted. 115

2. In an extensible table, a stationary slide, 120 a movable slide in operative engagement therewith, a leaf secured to the said movable slide, a table top normally overlying the leaf when in retracted position, a depending projection on the table top, a member on the movable slide with which the said projection in- 125

- 65 intermittently contacts to maintain the table top at a predetermined height when the leaf is being extended or retracted, a plate slidably mounted on the fixed slide having a cutout therein in alignment with the depending projection on the table top, a latch pivotally mounted on the said plate, a stop against which the latch normally abuts, spring means on the said plate to urge same and the latch 70 against the stop, a second plate slidably mounted on the first mentioned plate and provided with a cutout normally out of alignment with the cutout in the first mentioned plate, means on the movable slide for bringing 75 the cutout in the second mentioned plate into alignment with the cutout in the first mentioned plate when the said slide is nearing the end of its outward movement, a cam on the movable slide member to permit the depending 80 projection on the table top to enter the cutouts so that the said table top may gradually be lowered to a plane even with the leaf when the said leaf is partially retracted and an extension on the latch in the path of the 85 projection on the table top adapted to be actuated thereby to release the latch from its stop and swing the said latch to rest on top of the stop to permit the cutouts in the plates to assume their unaligned position when the leaf is again extended prior to retraction. 90
- 95 3. In an extensible table, a stationary slide, a movable slide in operative engagement therewith, a leaf secured to the said movable slide, a table top normally overlying the leaf, means on the table top to maintain same at a predetermined height while the leaf is being fully extended, a set of plates in sliding relation to each other mounted on the fixed slide and provided with cutouts normally out of alignment with each other, means on the movable slide to bring the said cutouts into alignment at a predetermined point of the outward travel of the said slides, and means on the movable slides to permit the table top to be lowered when the movable slides are partially retracted. 100
- 100 4. In an extensible table, a stationary slide, a movable slide on each side thereof and in engagement therewith, a leaf secured to each movable slide, means on the slides to produce a movement of the leaves in relatively opposite direction when actuated for expansion or retraction, a table top normally overlying the leaves, means on the table top to maintain same at a predetermined height while the leaves are being fully extended, a set of plates in sliding relation to each other mounted on each side of the fixed slides and provided with cutouts normally out of alignment with each other, means on the movable slides to bring the said cutouts into alignment at a predetermined point of the outward travel of the said slides, and means on the movable slides to permit the table top to be lowered when the movable slides are partially retracted. 105
- 110 5. In an extensible table, a stationary slide, a movable slide in operative engagement therewith, a leaf secured to the movable slide, a table top normally overlying the leaf, means on the table top to maintain same at a predetermined height while the leaf is being fully extended, a set of plates in sliding relation to each other mounted on the fixed slide and provided with cutouts normally out of alignment with each other, means on the movable slide to bring the said cutouts into alignment at a predetermined point of the outward travel of the said slide, and means on the movable slide to permit the table top to be lowered when the said movable slide is partially retracted. 115
- 120 6. In an extensible table, a stationary slide, a movable slide in operative engagement therewith, a leaf secured to the movable slide, a table top normally overlying the leaf, means on the table top to maintain same at a predetermined height while the leaf is being fully extended, a set of plates in sliding relation to each other mounted on the fixed slide and provided with cutouts normally out of alignment with each other, means for bringing the said cutouts into alignment at a predetermined point of the outward travel of the movable slide to permit the table top to be lowered, and means for again bringing the cutouts into their unaligned position prior to retraction of the table. 125
- 130 7. In an extensible table, a stationary slide, a movable slide in operative engagement therewith, a leaf secured to the said movable slide, a table top normally overlying the leaf when in retracted position, a depending projection on the table top, a member on the movable slide with which the said projection intermittently contacts to maintain the table top at a predetermined height when the leaf is being extended or retracted, a plate slidably mounted on the fixed slide having a cutout therein in alignment with the depending projection on the table top, a latch pivotally

mounted on the said plate, a stop against which the latch normally abuts, spring means on the said plate to urge same and the latch against the stop, a second plate slidably mounted on the first mentioned plate and provided with a cutout normally out of alignment with the cutout in the first mentioned plate, means on the movable slide for bringing the cutout in the second mentioned plate into alignment with the cutout in the first mentioned plate when the said slide is nearing the end of its outward movement and means on the movable slide to permit the gradual lowering of the table top and to permit the depending projection to enter the cutouts to trip the latch to again position the cutouts to their unaligned relation when the leaf is again extended prior to retraction.
